UNITED STATES PATENT OFFICE.

DONALD S. McCHESNEY, OF SYRACUSE, NEW YORK, ASSIGNOR TO HALL & McCHESNEY INC., OF SYRACUSE, NEW YORK, A CORPORATION OF NEW YORK.

LOOSE-LEAF BINDER.

Application filed March 14, 1927. Serial No. 175,188.

This invention relates to certain new and useful improvements in loose leaf binders.

The main object of the invention is the production of a loose leaf book in which 5 the posts, by reason of a novel and flexible construction, are readily capable of being extended or retracted to permit a tight confinement of the loose leaves in the book without regard to the number of leaves in 10 inserted or removed.

A further object resides in the fact that the flexible posts are movable in the end head of one of the book covers, and means is provided for readily and simultaneously 15 moving the posts to a greater or less extent through openings in the end head to permit the insertion of additional leaves by extension of the posts or the retraction of the posts when leaves are removed from 20 the book.

A further advantage resides in the particular form and construction of the flexible posts and the individual sections thereof.

Other objects and advantages relate to 25 the details of the structure and the form and relation to the parts thereof, all as will more fully appear from the following description, taken in connection with the accompanying drawings, in which:

30 Figure 1 is a perspective view of a book of this invention.

Figure 2 is a section on line 2—2, Figure 1.

Figure 3 is a section on line 3—3, Figure 2.

Figure 4 is a section on line 4—4, Figure 1.

Figure 5 is a view partially in section showing a portion of one of the flexible 40 posts and one of the racks.

Figure 6 is a sectional view through one of the posts taken at right angles to Figure 5.

Figure 7 is a sectional view through the 45 end head of one of the covers showing the mechanism for retracting and extending the posts.

The loose leaf book as illustrated comprises two covers —1— and —2— pivotally 50 mounted upon respective binder heads —3— and —4—. These binder heads are preferably of similar form and shape, and each comprises a tubular body portion —5— and end caps —6— secured to the opposite end 55 of the tubular body portion —5—, and ex-

tending forwardly therefrom, and the forwardly extending portions support pivot rods —7— extending between the caps —6— and upon which the rear end of covers —1— and —2— respectively are pivotally mounted.

These covers —1— and —2— may be formed of cardboard sheets —8— to which a metallic strip —9— is secured as by rivets —10— and the strips —9— extend rearwardly from the cardboard sheets —8— and are return-bent to form bearings for the pivot rods —7— so that the covers —1— and —2— can be turned about the pivot rods —7— to expose the bound leaves.

Preferably the sheet —8— and strip —9— have a suitable covering —11— of leather or other suitable material, and in like manner the tubular portions —5— of the binder heads —3— and —4— have a covering —12— of leather or other suitable material.

The binder head —4— in this particular illustration contains the mechanism for moving the flexible posts —13— and —14— and for this purpose racks —15— and —16— are arranged lengthwise of the binder head —4— near its front and rear sides, and are slidably mounted in similarly formed channel members —17— secured to the inner side of the wall of the binder head —4—.

Each rack in this particular disclosure includes an integral boss —18— adapted to receive a reduced cylindrical extension —19— upon the end of the first section —20— of the flexible post. These posts are of similar form, shape and construction, and a description of one constitutes a description of both. The first section —20— has its upper portion formed with a curved surface —21— preferably of spherical form, and this spherically formed upper portion is provided with a T-slot which extends up one side of the section and across the top of the section to a point beyond the axis of the section, and at the base of the T-slot there is an opening —22— permitting the sliding of a T-head —23— into the slot.

The remaining sections of the flexible post, except the last one —24—, are preferably 105 of similar form and shape, and each comprises a concave spherically formed lower end —25— provided with a depending T-head —23— adapted to slide in the T-slot in the section next below it.

The upper end of the additional sections 26 is formed with a convex curved surface preferably of spherical form, and the upper end of each section is in turn formed with a T-slot, and an opening leading to the slot of the same form and shape as the T-slot 27 and the opening 22.

In order to secure all of the sections together in a manner to permit movement of 10 the T-heads in the T-slots to produce a flexible post, each section is formed with an axial conduit 28, the upper end of which conduit opens into the T-slot in the upper end of the section and the lower end of 15 which extends through the T-head. This conduit is flared outwardly at its upper end on the side toward the opening 22 so that the next above T-head can slide in the T-slot in the section when all of the sections 20 are secured together, as for instance by a wire cable 29, the enlargement 30 of the conduit on the side adjacent the opening 22 permitting free movement of the cable 29 with the next above section as 25 the post is flexed by the movement of the T-heads in the T-slots.

The cable 29 may be secured to the first section 19 in any suitable manner, as by set screw 31 and by having its 30 end headed or riveted at 32 against the lower end of the section. The upper end of the cable 32 may be provided as best shown in Figure 2 with a headed end 33 engaging the base of a threaded recess 34 in the upper section 24, and this upper section may be closed by a headed screw 35 threaded into the recess in the section.

By removing the screw 35, additional 40 rigid extension sections may be threaded into the upper section 34 to lengthen the post, the extensions, however, being non-flexible. Each of the flexible posts is adapted to move longitudinally in opposite directions in the binder section 4 and are turned upwardly through openings 36 in the upper side of the binder section 4, which binder section has its wall bent downwardly to form a curved guide 37 for 45 guiding the flexible post into and out of the binder section 4, and in like manner the other binder section 3 is formed with openings or passageways 38 and 39 through which the upper ends of the posts 50 55 13 and 14 are adapted to extend, the heads of the screws 35 being of larger diameter than the passageways to thereby secure the upper ends of the posts from downward movement through the openings when loose leaves are clamped between the binder sections in the use of the book.

For the purpose of extending and retracting the flexible posts 13 and 14, means is provided for reciprocating the 60 racks 15 and 16 in opposite direc-

tions, and in this illustration this means takes the form of a gear 40 mounted upon a shaft 41 journaled in the upper and lower walls of the binder head 4, the gear 40 meshing with the oppositely disposed racks 15 and 16 for sliding the racks within the binder head as the shaft 41 is rotated.

For the purpose of rotating the shaft 41 a worm gear 42, integral with gear 40, is mounted on the shaft and meshes with a worm 43 formed on the shaft 44 journaled in bearings 45 carried from the interior of the binder head 4. This shaft is formed with collars 46 which prevent longitudinal movement of the shaft and the end 47 of the shaft is preferably square and is aligned with an opening 48 formed in the end cap 6 of binder head 4 so that by 50 the use of a key, the worm 43 can be manually rotated to thereby actuate the racks to move the flexible posts 13 and 14 to a greater or less extent into or out of the binder head 4.

It will be apparent that with this form of device it is only necessary that the posts should flex in one direction, and that by the use of the cooperating concave and convex portions on the sections of the posts, the 95 concave sections being provided with the T-heads and convex sections being provided with T-slots, that a comparatively permanent and rigid structure is produced which is capable of freely flexing in a direction to permit the posts to be pushed into or out of the binder head 4 along the guides 37 to extend or retract the posts in accordance with the thickness of the leaves to be bound in the book.

Altho I have shown and described a specific construction of apparatus as constituting a perhaps preferred embodiment of the invention, I do not desire to restrict myself to the details of form, construction or arrangement of the apparatus or the parts thereof, except as the same may be specifically included in the claims hereto appended.

I claim:

1. A loose leaf book comprising binder heads, covers pivotally connected to the binder heads, each of said binder heads being formed with openings, and flexible posts having end portions positioned in one 120 binder head and projecting outwardly therefrom and through the other binder head, and a pair of racks and a gear permanently mounted in the first of said binder heads for simultaneously extending and retracting 125 the posts.

2. A loose leaf book comprising binder heads, covers pivotally connected to the binder heads, each of said binder heads being formed with openings, and flexible posts 130

- having end portions positioned in one binder head and projecting outwardly therefrom and through the other binder head, a pair of racks and a gear mounted in the first 5 of said binder heads for simultaneously extending and retracting the posts, and a worm shaft extending through the first of said binder heads having an exposed end adapted to be operated for driving said gear.
- 10 3. A loose leaf book comprising a flexible post including a section having a curved head formed with a T-slot and a base formed with a T-head adapted to engage a T-slot in the next successive section.
- 15 4. A loose leaf book comprising a flexible post including a section having a convex curved head formed with a T-slot and a concave curved base formed with a T-head adapted to engage a T-slot in the next successive section.
- 20 5. A loose leaf book comprising a flexible post including a section having a convex spherical head formed with a T-slot and a concave spherical base formed with a T-head 25 adapted to engage a T-slot in the next successive section.
6. A loose leaf book comprising a flexible post including a plurality of sections having curved head portions formed with T-slots 30 and curved base sections having depending T-heads, the T-heads of one section being slidably inserted in the T-slots of the next
- section, and means for securing the sections together to permit sliding movement of the T-heads in the T-slots. 35
7. A loose leaf book comprising a flexible post including a plurality of sections having curved head portions formed with T-slots and curved base sections having depending T-heads, the T-heads of one section being 40 slidably inserted in the T-slots of the next section, said sections provided with a conduit extending from top to bottom thereof, and a cable extending through said conduit for connecting the sections together. 45
8. A loose leaf book comprising a flexible post including a plurality of sections having curved head portions formed with T-slots one end of said slots being cut away to permit the insertion therein of a T-head and 50 curved base sections having depending T-heads, the T-heads of one section being slidably inserted in the T-slots of the next section, each of said sections formed with a conduit extending from top to bottom thereof, 55 the upper end of the conduit adjacent the T-slot flaring toward the cut-away end of the T-slot, and means extending through said conduit for securing the sections together in a manner to permit the T-heads to 60 slide in the T-slots.

In witness whereof I have hereunto set my hand this 11 day of March 1927.

DONALD S. McCHESNEY.
